UNITED STATES PATENT OFFICE.

MICHAEL JUPIN, OF NEW BEDFORD, MASSACHUSETTS.

GAS BURNER FOR STARTING COAL FIRES.

Application filed January 14, 1928. Serial No. 246,796.

My invention relates to gas burner for starting coal fires, and aims to provide a novel and improved device of this character which may be conveniently placed in the ash pit of a coal stove or heater and supported on the bottom thereof so that the flames from the burners will ignite the coal and thus obviate the necessity of using wood for starting a fire.

Another object of the invention is the provision of a gas burner for starting fires, constructed in a manner for permitting the jets of flame to extend upwardly through the grate of a coal stove or heater in order that coal supported by said grate will be ignited, said burner being supported in position by an adjustable bar or lever pivoted to a base resting on the floor of the ash pit of the stove or heater, whereby said supporting bar may be adjusted for properly supporting the burner for use in stoves or heaters of different sizes.

It is also an object of the invention to provide a device of the above indicated character, which is simple and substantial in construction, which can be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a section through a stove illustrating my improved device arranged therein,

Figure 2 is a side elevation of the burner, showing a portion thereof in section,

Figure 3 is a fragmentary cross section taken on line 3—3 of Figure 2,

Figure 4 is a fragmentary cross section taken on line 4—4 of Figure 1, and

Figure 5 is a plan view of the base structure.

Referring to Figure 1 of the drawings, the numeral 10 designates a coal stove having a grate 11 arranged therein for supporting the fuel, as coal, and an ash pit 12 under the grate having a bottom 13 and an opening 14 leading into the same.

In carrying out my invention I employ a cylindrical gas chamber 15 which may be constructed of the usual gas pipes provided with end caps 16 threaded thereon and intermediate the ends of the chamber is a tap 17 into which is threaded one end of a gas feed pipe 18 bent to permit the same to extend through the opening 14 to the burner when located in the ash pit, said feed pipe being bent at the points indicated by the numeral 19. On the end of the gas feed pipe 18 opposite to that attached to the chamber 15 is a valve 20 for controlling said flow of gas to the chamber, and to this valve is attached a flexible tubing 21 connected to the main supply of gas.

On the upper side of the gas pipe forming the chamber 15 are a plurality of openings 22 into which are threaded upwardly extending gas spray nozzles 23 which taper towards their upper ends to provide restricted openings through which the gas passes. Supported upon each of the nozzles 23 is a dome-shaped member 24 into which air is permitted to enter and mix with the gas in order to provide the desired flame. In the interior of each of the dome-shaped members 24 is a collar 25 through the central opening 26 of which the nozzle 23 extends to support the dome-shaped member thereon, and said collar is provided concentrically with a plurality of openings 27 for permitting the air to pass therethrough. By referring to Figures 1 and 2 of the drawings, it can be seen that the dome-shaped members 24 are supported upon the nozzles 23 in a manner so that the lower edges thereof are spaced from the fuel chamber 15 so as not to interfere with the entrance of air into said dome-shaped members.

The upper portion of each dome-shaped member 24 is contracted to form a nipple 28 into which extends the upper end of the nozzle 23, and threaded on the upper end of each nipple is a four-way coupling 29 to which the gas burners 30 and 32 are connected, the burners 32 having intermediate pipe sections 31 by which they are spaced from the burners 30. The upper ends of the burners 30 are on the same plane with the upper ends of the burners 32, as clearly shown in Figure 1 of the drawings. It is to be noted by referring to Figures 1 and 2 that the burners 30 and 32 flare outwardly at their upper ends for increasing the width of the flames. It is also to be noted that

the branch burners are disposed transversely with respect to the fuel chamber and that the series of burners are arranged in parallel spaced relation so as to extend between 5 the bars of the grate 11 as clearly shown in Figure 1 of the drawings for efficiently igniting the coal supported by said grate.

In order that the gas burner device will be properly supported with relation to the 10 coal in the stove or heater, I have provided a supporting structure generally designated by the numeral 33 comprising a main bar 34 pivotally connected to the gas feed pipe 18 by means of a metal clip 36 through the 15 ears 35 of which the clamping bolt 37 passes and is extended at one side to receive the supporting bar or lever 34, the nut 39 of the bolt for clamping the clip to the feed pipe being interposed between the supporting 20 bar and adjoining ear of the clip, and on the outer end of said bolt is a clamping nut 40 having a handle 42 by which it is turned to clamp the parts together. It can be seen that by loosening the clamping nut 25 40 the supporting bar or lever may be adjusted to various positions with relation to the gas feed pipe, and for the purpose of manipulating this lever the outer end thereof is in the form of a handle 43. The supporting 30 bar is bent at an angle near its lower end and pivoted to a substantial base 45 adapted to rest on the bottom 13 of the ash pit 12. The base 45 has a pair of upwardly extending ears 46 between which the supporting 35 bar or lever is connected thereto in such manner as to provide for adjustment. Through the ears 46 and the end 44 of the bar 34 are a series of openings through which bolts 47 are passed for adjustably 40 connecting the parts together. It can be seen that by arranging the openings as clearly illustrated in Figure 1 of the drawings the angle of the supporting bar or 45 lever with relation to the base may be varied so that the device may be used in connection with stoves and heaters of different sizes.

In order to further aid in supporting the 50 base burner against movement with relation to the supporting bar, a collar 48 is fixed on the gas feed pipe 18 and has a pair of depending ears through which a bolt 50 extends for connecting thereto a prop 51 the 55 lower end of which is adapted to be swung into engagement with teeth 52 on the upper edge of the supporting bar. By this arrangement it can be seen that the prop 51 may be swung to position for engaging the 60 teeth 52 after the supporting bar has been adjusted on the base and will aid in supporting the structure against movement, and thus support the burners 30 and 32 in proper position with relation to the grate and coal 65 in the stove or heater.

When it is desired to start a fire in a coal stove or heater, the device is placed in the ash pit to rest on the bottom thereof, and in handling it for this purpose the outer end of the gas feed pipe 18 and the handle 70 portion 43 of the bar 34 are grasped for swinging the bar 34 on its pivot to bring the base against the main fuel pipe 18 for passing the device through the opening 14 and on to the floor 13 of the ash pit, the bars or 75 lever being then manipulated to position the burners 30 and 32 between the bars of the grate 11. By tightening the clamping nut 40 movement of the bar 34 with relation to the pipe 18 is prevented, and swinging the prop 51 to position to engage the teeth 52, it can be seen that the device will be supported so that flames from the burners will 80 ignite coal placed on the grate. When it is desired to use the device in connection with 85 stoves or heaters having ash pits of different heights, the base member 45 may be adjusted with relation to the bar 34 by removing the bolts 47 which connect the base member with the bar 34 and inserting the 90 bolts through other holes in the ears 46 of the base member and holes in the end 44 of the bar 34. When the valve 20 is opened 95 gas will flow through the feed pipe 18 to the chamber 15 and from the latter out through the nozzles 23 to the burners 30 and 32. As the gas passes from the nozzles 23, air entering the lower ends of the dome-shaped members 24 will be mixed therewith so as to provide a combustible mixture for igniting the coal supported on the grate. 100

Having thus described my invention, what I claim as new is:

1. A portable gas burner for use in starting the burning of fuel in stoves, comprising a gas pipe having a series of burners rising therefrom in spaced parallel relation to each other, and a feed pipe connected to said gas pipe; together with a supporting base, a supporting bar or lever attached to the supporting base and pivotally connected to the intermediate portion of the feed pipe for swinging movement of the gas burner to and from the said supporting base, and means for supporting the gas burner in adjusted position with respect to the supporting bar and base. 115

2. A portable gas burner for use in starting the burning of fuel in stoves, comprising a gas pipe having a series of burners rising therefrom in spaced parallel relation to each other, and a feed pipe connected to said gas pipe; together with a supporting base, a supporting bar pivotally connected to an intermediate portion of the feed pipe, means for attaching the supporting bar adjustably to the base, and means supporting the gas burner in adjusted position with respect to the supporting bar and base. 120

3. A portable gas burner for use in start- 125

ing the burning of fuel in stoves, comprising a gas pipe having a series of burners rising therefrom in spaced relation to each other, and a feed pipe connected to said 5 gas pipe; together with a supporting base, a supporting bar pivotally connected at an intermediate portion thereof to an intermediate portion of the feed pipe to provide a handle at the outer end of said supporting 10 bar, means for adjustably connecting the lower end of the supporting bar to the base, and means for securing the feed pipe and supporting bar in adjusted position with respect to each other.

15 4. A portable gas burner for use in starting the burning of fuel in stoves, comprising a gas pipe having a series of burners rising therefrom in spaced relation to each other, and a feed pipe connected to said gas 20 pipe; together with a supporting base, a supporting bar pivotally connected at an intermediate portion thereof to an intermediate portion of the feed pipe to provide a handle at the outer end of said supporting 25 bar, a bolt forming the pivotal connection, and a clamping nut on the bolt to secure the parts firmly together, whereby the burner and base may be brought together for passing the device through the opening leading 30 into the ash pit of the stove.

5. A portable gas burner for use in starting the burning of fuel in stoves, comprising a gas pipe having a series of burners rising therefrom in spaced relation to each 35 other, and a feed pipe connected to said gas pipe; together with a supporting base, a supporting bar pivotally connected at an intermediate portion thereof to an intermediate

portion of the feed pipe to provide a handle at the outer end of said supporting 40 bar, a bolt forming the pivotal connection, a clamping nut on the bolt to secure the parts together, and a prop interposed between the feed pipe and supporting bar.

6. A portable gas burner for use in starting the burning of fuel in stoves, comprising a gas pipe having a series of burners rising therefrom in spaced relation to each other, and a feed pipe connected to said gas 50 pipe; together with a supporting base, a supporting bar pivotally connected to said feed pipe and having teeth on its upper edge, a bolt forming the pivotal connection between the supporting bar and feed pipe, a clamping nut on the bolt to secure the 55 parts together, and a prop pivoted to the feed pipe to engage the teeth on the supporting bar.

7. A portable gas burner for use in starting the burning of fuel in stoves, comprising a gas pipe having a series of burners rising therefrom in spaced relation to each other, and a feed pipe connected to said gas 60 pipe; together with a supporting base, a supporting bar and means for adjustably connecting the same to the base, said supporting bar being pivotally connected to said feed pipe and having teeth on its upper edge, a bolt forming the pivotal connection between the supporting bar and feed pipe, 70 a clamping nut on the bolt for securing the parts together, and a prop pivoted to the feed pipe to engage the teeth on the supporting bar.

MICHAEL JUPIN.
